[57] CLAIM

The ornamental design for a demand controller component, as shown and described.

DESCRIPTION

FIG. 1 is a front elevation of the demand controller component showing my new design.

FIG. 2 is a bottom plan view of the structure of FIG. 1. FIG. 3 is a top plan view of the structure of FIGS. 1 and 2.

FIG. 4 is a side elevation of the left side of the demand controller component as viewed in FIG. 1.

FIG. 5 is a side elevation of the right side of the demand controller component as viewed in FIG. 1.

FIG. 6 is a perspective view of the structure illustrated in FIG. 1 showing the top, front and right sides.

FIG. 7 is a perspective view of the structure illustrated in FIG. 1 showing the bottom, front and the left sides. The rear of the demand controller component is without ornamentation.
